(No Model.)

S. F. WEBB.
ANIMAL POKE.

No. 598,352.

Patented Feb. 1, 1898.

UNITED STATES PATENT OFFICE.

SAMUEL F. WEBB, OF POND CREEK, OKLAHOMA TERRITORY.

ANIMAL-POKE.

SPECIFICATION forming part of Letters Patent No. 598,352, dated February 1, 1898.

Application filed June 7, 1897. Serial No. 639,748. (No model.)

To all whom it may concern:

Be it known that I, SAMUEL F. WEBB, a citizen of the United States, residing at Pond Creek, in the county of L and Territory of Oklahoma, have invented certain new and useful Improvements in Animal-Pokes; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to animal-pokes, its object being to improve the construction of devices of this character whereby they may be adjusted to fit the necks and heads of different animals.

20 The invention will be fully described hereinafter and its novel features pointed out in the subjoined claims.

In the drawings, Figure 1 is a perspective view of my improved poke in position on an 25 animal. Fig. 2 is a perspective view, on an enlarged scale, of the poke detached. Fig. 3 is a similar view showing a slight modification and partly broken away, and Fig. 4 is a detail view of the spring-hinge of the neck-yoke.

30 Similar reference-numerals indicate similar parts in the several figures.

The neck-yoke is oblong and substantially rectangular in form, and consists of two parts (indicated by 1 and 2) which are hinged together at the lower end of the yoke and have a hook-and-eye connection at the upper end of the yoke, as will be particularly described hereinafter. Each of these parts 1 and 2 is formed of two sections adjustably connected 40 together, in order that the yoke may be lengthened or shortened, as desired. The parts 1 and 2 are formed of wire, and the upper section of the part 1 comprises the vertical arm 3, having a hook 4 at its upper end and an eye 5 at its lower end. From the eye 5 the wire extends a short distance horizontally, as indicated at 6, and is then bent at substantially a right angle to form a vertical part 7, which constitutes a portion of one vertical side of the 45 yoke. Two eyes 8 and 9 are formed in the part 7 between its upper and lower ends. The lower section of the part 1 comprises the

vertical part 10, the upper end of which overlaps the lower end of the part 7 and constitutes the remaining portion of one vertical side of the yoke. The wire is then bent inwardly to form a substantially horizontal part 11 equal in length to the part 6, and is then bent to form an eye 12, from which the hooked arm 13 extends downwardly. 55 60

The upper section of the part 2 comprises the horizontally-disposed hook 14, adapted to detachably engage the eye 5, a horizontal part 15, and the vertical part 16, the latter forming a portion of the other vertical side 65 of the yoke and having two eyes 17 and 18, formed therein between the upper and lower ends substantially opposite the eyes 8 and 9. The lower section of the part 2 comprises the vertical part 19, the upper end of which overlaps the lower end of the part 16 and constitutes the remaining portion of the vertical side of the yoke. This wire is then bent inwardly toward the eye 12 and its end is bent to form a series of coils, (indicated by 20,) 70 75 which are engaged in the eye 12, and the coil 20 and the eye 12 will form a spring-hinge for the lower ends of the parts 1 and 2, the spring being so arranged that the upper ends of the parts 1 and 2 will normally tend to spread 80 apart.

When the hook 14 is engaged with the eye 5, it will be seen that the spring-hinge normally tends to hold them in close engagement, and in order to release the hook 14 from the 85 eye the upper ends of the parts 1 and 2 must be moved toward each other against the force of the spring-hinge. The yoke can therefore be quickly secured on or removed from the neck of the animal, but when in place on the 90 animal will not be liable to be accidentally detached.

In order to lock the respective overlapping ends of the upper and lower sections of the parts 1 and 2 together, one of each pair of 95 overlapping ends will be provided with small plates or lugs 21, rigidly secured to it and perforated for the passage of the other overlapping end, and a set-screw 22 will be provided in each plate or lug to engage and lock 100 the sliding overlapping end to the lug or plate. In this manner the length of the yoke can be adjusted as circumstances may require.

The cheek-pieces of the poke are alike on

each side of the device and are pivotally connected to the eyes 8 and 9 and 17 and 18, respectively. A description of one will suffice for both. A short rod 23 is provided with an eye at one end engaging the eye 8, and its other end is slidably supported in an opening in a plate or lug 24, secured to a rod 25, and a set-screw 26 in the plate or lug serves to lock it and the rod 23 together. The rod 25 has a hook 27 at its inner end, which embraces the rod 23 and forms a slidable connection between the two rods. The rod 25 is also provided with an eye 28 intermediate its ends and another eye 29 at its outer end. Two rods 30 and 31 are respectively connected to the eyes 9 and 28. These rods overlap each other and are adjustably connected together in the same manner as are the rods 23 and 25. The cheek-pieces are therefore adjustable as to length, and the device can therefore be used on heads of different lengths.

The nose-yoke 32 consists, preferably, of a piece of wire bent upon itself and twisted to form a rope which is bent into substantially ²⁵ U shape and pivotally connected at its ends to the eyes 29 at the forward ends of the cheek-pieces. The two arms 33 of the nose-clamp are preferably formed by the ends of the wire out of which the nose-yoke is made, and they ³⁰ are therefore integral with the yoke. The arms are bent inwardly toward each other in order to enter the nostrils of the animal, and their extreme ends are bent, as indicated at 34, to form a round smooth engaging surface ³⁵ with the nostril in order to avoid giving the animal unnecessary pain. The arms will preferably be of spring metal and are provided with a ring 35, which slidably fits over them and serves to hold them securely in engagement with the nostrils of the animal.

As shown in Fig. 3, the nose-yoke is provided with a series of short arms 36, which are firmly attached to it and have their outer ends pointed or sharpened, as indicated at 37. ⁴⁵ Cows will sometimes suck their teats, and these pointed arms are designed to prevent them from doing so. These arms 36 also may be used on pokes worn by sucking calves and will serve to wean them.

From the foregoing description it will be apparent that a poke made in accordance with my invention may be adjusted to properly fit the animal and therefore may be worn by it without any inconvenience unless it should ⁵⁰ attempt to pass through a fence.

Pokes that do not properly fit the animal inflict unnecessary pain upon it, and hence it is important that they may be capable of

easy adjustment to properly fit the neck and also to have the proper length in the connection between the neck-yoke and the nose-clamp. ⁶⁰

Having described my invention, I claim—

1. In an animal-poke, a neck-yoke formed of two parts, a spring-hinge connecting said parts at one end, and a detachable connection at their other end, and hooked arms extending from the yoke, combined with cheek-pieces, a nose-yoke and a nose-clamp, substantially as described. ⁷⁰

2. In an animal-poke, a neck-yoke formed of two parts, each part consisting of upper and lower sections adjustably connected together, a spring-hinge connecting said parts at one end, and a detachable connection at their other end, said yoke being provided with hooked arms, combined with cheek-pieces, a nose-yoke and a nose-clamp, substantially as described. ⁷⁵

3. In an animal-poke, a neck-yoke formed of two parts hinged together at one end and detachably connected at their other end, said yoke being provided with hooked arms, combined with a nose-clamp, a nose-yoke connected to said clamp, and cheek-pieces connecting the neck-yoke to the nose-yoke, said cheek-pieces each being formed of two sections adjustably connected together, substantially as described. ⁸⁵

4. In an animal-poke, a neck-yoke formed of two parts, a spring-hinge connecting said parts at one end and a hook-and-eye connection at their other end, each part consisting of two sections adjustably connected together, and one of said parts having integral hooked arms, combined with a nose-clamp, a nose-yoke connected to the clamp, and cheek-pieces connecting the nose-yoke to the neck-yoke, each cheek-piece consisting of two sections adjustably connected together, substantially as described. ⁹⁰

5. In an animal-poke, a neck-yoke having hooked arms extending therefrom, combined with cheek-pieces hinged to the neck-yoke, a nose-yoke hinged to the cheek-pieces, a nose-clamp integral with the nose-yoke, and a series of arms having pointed or sharpened outer ends connected to the nose-yoke and projecting therefrom, substantially as described. ¹⁰⁵

In testimony whereof I affix my signature ¹¹⁰ in presence of two witnesses.

SAMUEL F. WEBB.
